[57] CLAIM

The ornamental design for a wire toothbrush holder, as shown and described.

DESCRIPTION

FIG. 1 is a perspective view of a wire toothbrush holder showing our new design, the suction cups shown in phantom lines not forming part of the invention;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof; and,

FIG. 7 is a rear elevational view thereof.
